UNITED STATES PATENT OFFICE.

WILLIAM S. AUD, OF HERNDON, VIRGINIA, ASSIGNOR OF ONE-SIXTH TO JENNIE A. AUD, ONE-SIXTH TO DAVID M. AUD, ONE-SIXTH TO MARY A. HUTCHISON, ONE-SIXTH TO JESSE V. AUD, AND ONE-SIXTH TO JENNIE L. CURTICE, ALL OF SOUTH BOSTON, VIRGINIA.

LIFE-SAVING SUIT.

Application filed May 25, 1927. Serial No. 194,210.

This invention relates to life saving suits, and particularly to means for closing the entrance opening thereof, and one object of the invention is to provide a novel and improved construction of sealing and fastening means whereby the meeting edges of the entrance opening of the garment may be securely fastened and sealed against the admission of water.

10 A further object of the invention is to provide a suit adapted for life saving, swimming and analogous purposes, which may be quickly, easily and conveniently applied, and in which the meeting edges of the entrance opening may be closed and sealed without trouble or material exertion on the part of the operator.

15 The invention consists of the features of construction, combination and arrangement 20 of parts, hereinafter fully described and claimed, reference being had to the accompanying drawings, in which:—

25 Figure 1 is a front view of the suit as applied for use and showing the entrance opening partly closed.

Figure 2 is a similar view showing the entrance opening fully closed and the collar fastened about the neck of the wearer.

30 Figure 3 is a perspective view on an enlarged scale of the upper portion of the garment.

Figure 4 is a fragmentary view in elevation looking toward one side of the closure of the entrance opening.

35 Figure 5 is a view in elevation looking toward the inner face of one of the sealing strips.

Figure 6 is a fragmentary perspective view showing the inner faces of the sealing strips and the members of one of the fasteners.

40 Figures 7, 8 and 9 are sections taken, respectively, on the lines 7—7, 8—8 and 9—9 of Figure 4.

45 Referring now more particularly to the drawings, 1 designates a life saving suit of integral or union type, in which the trousers portion 2 and jacket portion 3 of the suit are permanently united. The legs of the trousers portion 2 as shown, terminate in foot portions, socks or boots 4, while the packet portion 3 is provided with sleeves 5 terminating in gloves or mittens 6. The jacket portion 3

is provided at the front with an entrance opening 7, and is provided at its upper portion with a collar or neck band 8. This collar or neck band may include a section 9 of elastic material, and a strip or other fastening member 10 may be employed, with suitable tongue and buckle connections, for adjustably securing the collar or neck band about the neck of the wearer. All of such parts of the suit, with the exception of the strip 10 and its connections, are made of some suitable strong and durable waterproof material, such as soft vulcanized rubber or any suitable combination of rubber and fabric, any seams used for uniting the parts where necessary being of water-tight character.

Along the margins of the entrance opening 7 are provided sealing strips 11 and 12, which extend the full length of the opening from a point adjacent to the crotch portion to the upper edge of the collar 8 of the garment. These sealing strips 11 and 12 are also made of rubber or rubber and fabric, of a proper degree of flexibility and rigidity to maintain their shape. Preferably these sealing strips are secured below the collar portion to backing or reinforcing strips 13 and 14 whereby they are strengthened and their deformation under pressures and strains prevented. The backing or reinforcing strips are also preferably made of rubber or rubber and fabric of a suitable degree of rigidity and serve as supports for the fastening devices employed for holding the sealing strips united to close the opening 4 and to maintain the sealing elements thereon permanently in contact to prevent the entrance of water.

As shown, the fastening devices consist of a series of keeper members 15, mounted on the strip 11 and backing 13, and a coacting series of locking plates 16 mounted on the sealing strip and backing 12 and 14. The keeper members 15 are in the form of eyelets linked in a vertical direction parallel with the sealing strips, and the locking members 16 are in the form of plates adapted to pass through said keeper members and to engage the same for a locking action. The slots or passages of the eyelets 15 are of flaring form between the inner and outer surface of each eyelet, so as to accurately guide the coacting locking plate into engagement therewith.

Each locking plate 16 is provided at its lower edge with a series of ratchet-shaped locking teeth 17 for adjustable locking engagement with the lower wall of the eyelet at its outer side beyond which the applied locking plate projects, when fully inserted, the shape of the teeth being such as to adapt the plate to be freely applied while holding it from casual separation after the locking action. The locking plates are adapted to be inserted by bringing the sealing strips together with a certain degree of forcing pressure, in which operation the inclined surfaces of the teeth of each locking device slide over the lower wall of each keeper, the final teeth of the locking devices, when the latter are fully applied, dropping by gravity and presenting their straight shoulders for engagement with the outer surfaces of the keepers to hold the sealing strips compressed together and securely locked. A releasing action may be effected, however, by compressing the strips and raising one relatively to the other, whereupon the fasteners may be disengaged and the sealing strips moved apart to spread the opening 7 and thus allow the suit to be removed. With the construction described, it is merely necessary to apply the suit to the person, in which operation the operator steps through the entrance opening into the trousers portion of the garment and then inserts his arms into the sleeves and draws the jacket portion 3 about him, and then properly adjusts the collar 8, after which by merely pressing upon the sealing strips at the points where the fasteners are located an instantanous closing and locking action will be effected. The projecting ends of the strips 11 and 12 lying above the upper ends of the backing strips 13 and 14 are of greater flexibility than those portions of the sealing strips reinforced by the backing strips to adapt them to permit free movements of the collar or neck band 8. These upper projecting portions of the strips 11 and 12 are provided with a keeper and fastener of the character described for locking and sealing connection.

Means are provided upon the inner faces of the sealing strips 11 and 12 for effecting a tight sealing connection between them when fastened together, in order to provide an absolutely water-tight joint. The sealing means shown consists of a pair of spaced parallel sealing ribs 18 and 19 upon the inner face of the strip 11 and a coacting pair of ribs 20 and 21 upon the inner face of the strip 12. The ribs 18 and 19 are preferably made of semi-elastic rubber or rubber and fabric, while the ribs 20 and 21 which they respectively engage are of special construction. These ribs 20 and 21 are of much greater breadth than the ribs 18 and 19 and are provided with central longitudinal grooves or processes to receive the rounded outer edges of the ribs 18 and 19, whereby, in addition to

the locking connection the sealing strips, when coupled, will be held from lateral shifting or displacement, while at the same time the received portions of the ribs 18 and 19 will form a water-proof joint connection with the ribs 20 and 21. Preferably inner and outer sets of ribs are provided, as shown, in order to secure double assurance against the entrance of water, the inner ribs serving to effectually prevent any entrance of water which might possibly creep past the outer ribs. The rib 21 of the strip 12 preferably comprises a hollow cover or face portion 22 which is or may be integral with the strip 12 and a backing portion 23 of a material having a high degree of elasticity, such as sponge rubber. The rib 20 may be of the same construction as the rib 21, but preferably is of solid character, so that it is of a greater degree of stiffness or rigidity than the cushioned rib 21. When the rib 19 is brought under pressure into engagement with the rib 21 the elastic backing 23 will allow the cover portion 22 to recede under the pressure of the rib 19, thus deepening the groove in said rib 21 and allowing the rib 19 to project thereinto to a greater extent, and with the result that the sealing surfaces are not only increased but the backing 23 is maintained under tension to constantly keep the sealing surfaces of the ribs in contact to maintain at all times the watertight integrity of the joint. As stated, the rib 20 may be of the same construction as the rib 21 and have the same action, but is preferably made, as shown, solid and stationary, so that, when the sealing strips are brought together, and the fasteners interlocked, the rib 21 being more resistant to the pressure of the rib 18, will allow the sealing strips to rock to a certain degree on the ribs 18 and 20 as an axis so as to adapt the ribs 19 and 21 to be brought still closer together and have a tight sealing action.

Figure 1 shows the suit applied for use with the two lower fasteners of the four fasteners shown locked, while Figure 2 shows the suit applied with all four fasteners locked and the collar or neck band drawn snugly about the neck of the wearer. From an inspection of these views, it will be apparent that after the suit has been drawn upon the person of the wearer, it is only necessary for the wearer, starting at the lower ends of the sealing strips, to bring the strips together under a certain degree of pressure, whereby the fasteners are interlocked, upon the completion of which action the strips 11 and 12 will be firmly pressed together to hermetically close the opening 7. The use of fastening devices of the type disclosed which are always in position for use, obviates the necessity of employing auxiliary fastening means, or of adjusting fastening devices lengthwise of the strips, and also obviates the necessity of employing fasteners of a type liable to

drop off and thus become misplaced or lost. The sealing ribs between the strips, being held tightly pressed by the locked fasteners, prevent access of any moisture to the interior of the suit, no matter how long the suit is worn, so that absolute safety in the use of the suit is ensured. While but a single pair of ribs upon the coacting sealing strips may be employed, I preferably use two pairs of strips, as shown, in order to add to the security of the connection. It is obvious, of course, that fastening and sealing means of any equivalent type, falling within the scope of the appended claims, may be employed without departing from the spirit or sacrificing any of the advantages of the invention.

Having thus fully described my invention, I claim:

1. A life saving suit having an entrance opening, closure strips along the marginal edges of said opening, said strips having sealing faces, slotted keeper members upon one of said strips, and fastening members upon the other strip adapted to be passed through said slotted keeper members and each having a plurality of locking surfaces for adjustable engagement with its keeper member.

2. A life saving suit having an entrance opening, closure strips along the marginal edges of said opening, said strips having sealing faces, slotted keeper members upon one of said strips, and locking members upon the other strip comprising plates adapted to be passed through said slotted keeper members, each locking plate having a ratchet toothed surface for engagement with the coacting keeper member.

3. A life saving suit having an entrance opening, keeper strips along the marginal edges of said opening, said strips having sealing faces, slotted keeper members upon one of the strips, and locking members upon the other strip comprising plates adapted to be passed through the slots in the keeper members, each plate having a toothed locking surface for locking engagement with the coacting keeper member.

4. A life saving suit having an entrance opening, closure strips along the marginal edges of said opening, pairs of opposed outer and inner resilient sealing ribs upon said strips, and fastening means for connecting

the strips and holding said ribs pressed tightly into engagement with one another.

5. A life saving suit having an entrance opening, sealing strips along the marginal edges of the opening, inner and outer resilient sealing ribs upon one of said strips, said ribs having rounded faces, outer and inner sealing ribs upon the other strip having grooves to receive the rounded faces of the first-named ribs, and fastening means for uniting the strips and holding said ribs pressed together.

6. A life saving suit having an entrance opening, sealing strips along the marginal edges of said opening, resilient sealing ribs upon the opposed faces of said strips, slotted keeper members upon one of the strips, and toothed fastening members upon the other strip for interlocking engagement with said keeper members.

7. A life saving suit having an entrance opening, closure strips along the marginal edges of the opening, spaced outer and inner elastic sealing ribs upon the opposed faces of said strips, slotted keeper members upon one of the strips between the ribs thereof, and fastening members upon the other strip between the ribs thereof for engagement with said slotted keeper members.

8. A life saving suit having an entrance opening, sealing strips along the marginal edges of said opening, an elastic sealing rib upon one of said strips, a grooved rib upon the other strip adapted to receive the first-named rib and including a body of elastic material compressible under pressure when the ribs are brought together, and fastening means upon the strips for holding them connected.

9. A life saving suit having an entrance opening, sealing strips along the marginal edges of said opening, inner and outer ribs extending along one of said strips, said ribs having contact faces, inner and outer ribs upon the other strip having grooved faces to receive the contact faces of the first-named ribs, one of said grooved ribs being of greater elasticity than the other, and fastening means upon the strips for holding them connected and pressing the ribs firmly together.

In testimony whereof I affix my signature.

WILLIAM S. AUD.
